DRILL BIT

John F. Shaw, Los Angeles, Calif., assignor to
 Reed Roller Bit Company, Houston, Tex., a
 corporation of Texas

Application June 2, 1939, Serial No. 276,963

7 Claims. (CL 255—71)

This invention relates to drill bits, and has particular reference to bits of the roller type, wherein roller cutters are rotatably mounted on the bit head and are provided with cutter teeth which dig into the formation as the cutters roll thereupon.

The general object of this invention is to provide a novel and advantageous structure which may be more readily assembled and which will 10 provide a more effective and durable drill than those in use heretofore.

In the type of drilling bit known as a cross roller bit there are customarily provided a pair of side cutters adapted to cut at the sides of 15 the bottom of the hole and located in positions which are substantially diametrically opposite each other with respect to the bit head. Between these two cutters and extending transversely with respect to a line drawn between them 20 there is ordinarily a cross roller cutter pin on which are mounted a plurality of cross roller cutters adapted to cut the central portion of the bottom of the hole. These cross roller pins are normally disposed on a plane substantially at right angles to the axis of rotation of the bit and when the bit is in vertical position the cutter pins and cross roller cutters mounted thereon will have their axes disposed substantially horizontally and in alignment with each other.

In the usual type of bit just described the axial 30 extent of the side cutters is limited by the presence between the side cutters of the cross roller cutters. Considerable difficulty has been experienced with the bearings of the side cutters because of this necessarily limited axial extent of 35 the side cutters. Specifically, it has been proposed that the side cutters be provided with radial bearings of the friction type in a position spaced inwardly from the usual anti-friction bearings.

It is an object of this invention to provide a 40 structure of the general type set forth in which there will be a greater amount of room for the side roller cutters and bearings therefor. More specifically, it is an object of this invention to provide a structure in which there will be a greater 45 amount of room than in the usual construction for a friction bearing such as above described.

In addition to the foregoing, it is an object of 50 this invention to provide a structure in which the outer supports for the cross roller cutter pins will be stronger and more durable than in previous constructions.

Another object of this invention is to provide

a drill bit structure in which the cutters and their bearings and supporting means may be assembled and secured together as a unit, after which they may be handled as a unit and assembled with respect to the body of the drill. 5

In the drawings:

Fig. 1 is a vertical cross section illustrating a bit constructed in accordance with this invention.

Fig. 2 is a partial vertical cross section taken 10 substantially at right angles to Fig. 1 and showing the structure of the side cutter mounting of the bit illustrated in Fig. 1.

Fig. 3 is a view showing the bit head before 15 the cutter and bearing assembly has been secured thereto.

Fig. 4 is a view showing the cutter and bearing assembly prior to mounting upon the bit head.

Referring now more in detail to the drawings, 20 the numeral 1 designates the bit body and the numeral 2 the threaded shank thereof by which it is connected to the lower end of the drill stem. Extending downwardly from each of the four sides of this body member are arms, two of which 25 are designated by the numeral 3 and the other two by the numeral 4. Each of the arms 3 and 4 is provided with a flat outer surface and with an inclined shoulder at the upper end thereof for the purpose of receiving supporting arms to 30 be welded or otherwise secured thereto as will be presently described.

The cutter and bearing assembly which is illustrated in side elevation in Fig. 4 consists of a 35 pair of cross roller cutters 5 and 6 and a pair of side roller cutters 7 mounted upon suitable bearing supports adapted to be connected to the head 1. The bearings for the cross roller cutters consist of cutter pins 8 and 9, respectively, the cutter pin 8 being formed in this 40 instance integral with an upstanding arm 10 and the cutter pin 9 being formed with a similar arm 11. These pins are, of course, straight throughout their length and extend downwardly and inwardly as clearly illustrated in Fig. 1 and their inner ends are disposed in an opening in a bridge member 12 which extends transversely of the head and substantially at right angles to a line between the arms 10 and 11. The ends of the 45 shafts 8 and 9 may be welded together within the opening in the bridge as shown at 13, or they may be otherwise held in this opening by any suitable means. The cross roller cutters 5 and 6 are of such length or extent as to traverse sub-

stantially the entire area of the bottom of a hole within the path of said side cutters.

The opposite ends of the bridge are provided with suitable spindles for the reception of the side cutters 7. These spindles have axes extending downwardly and inwardly with respect to each other, and it will readily be observed that there will be a greater space available longitudinally of these axes by virtue of the fact that the cross cutter pins extend downwardly and inwardly, than there would be if these cutter pins extended substantially horizontally in the usual manner. It is, therefore, possible to make these spindles longer by virtue of the present construction.

15 The shafts 8 and 9 which support the cutters 5 and 6, respectively, are each formed in the usual manner with races for roller bearings 14 and 15 adapted to take the radial load from these cutters respectively, and with a race for a ball bearing 16 adapted to take the outward end thrust from these cutters.

The spindles for the side cutters 7 are each provided with a circumferential groove 17 adapted to receive ball thrust bearings 18 and 25 with a roller race 19 of reduced diameter to receive the roller bearings 20. The ball bearings 18 fit the groove 21 forming a raceway in the interior of the cutter 7 and are adapted when in place to take the end thrust of this cutter. The 30 outer ends of the spindles just described extend beyond the side cutter 7 and are adapted to be received within openings in the side supporting arms 22 which extend upwardly therefrom. These side supporting arms are adapted to be welded as 35 at 23 to the outer ends of the spindles respectively. Each of the side supporting arms is also provided with an opening adapted to receive a dowel pin 24 which in turn will register with an opening in one of the arms 3 of the bit head when the bearing assembly occupies the proper 40 position with respect to the bit head.

By virtue of the additional space made available for the side cutters by the downwardly and inwardly inclined disposition of the cross cutter pins, there is provided a greater amount of room 45 so that the side cutters may extend a greater distance axially than in previous constructions. By virtue of this greater extent, ample room is provided for additional bearing upon the spindle. This additional bearing upon the spindle is shown in the present example in the form of a friction bearing, the cutter being formed with a part 28 inwardly of the race 21 adapted to bear directly upon a friction bearing surface 29 formed 50 on the spindle. This of course provides a more sturdy bearing structure for the side cutters and one better capable of taking the tremendous radial load imposed upon these cutters in operation.

60 In addition to the above, the inclination of the cross roller cutter pins makes it possible to use arms 10 and 11 which are of greater cross section area above the point where the cutter pins are joined thereto than would be the case if these 65 cutter pins were horizontal. That is, when the cutter pins are inclined as shown in Fig. 1, the arms 10 and 11 just above the outer ends of these cutter pins may be made with greater radial dimensions than if these pins were horizontal, without interfering with the action of the cutters. 70 This of course produces a much stronger and sturdier support for the cross cutter pins and makes possible a more durable bit construction.

It will be seen that when the cutter and bearing assembly has been made up as just described

and is in the condition illustrated in Fig. 4, this assembly may be moved as a unit onto the bit head with the respective arms 10, 11 and 22 in engagement with and seated upon the arms 6 and 3 on the bit head. When the assembly is in 5 proper position the dowels 24 may be inserted to temporarily hold this assembly in place and these dowels welded in as shown at 25. The arms 10, 11 and 22 may then be welded to the bit head as shown at 26 and 27 respectively, after which 10 the bit is ready for operation.

It will readily be seen from the foregoing that a means has been provided whereby the cross roller cutters of a roller bit may be disposed so as to provide more room for the side cutters 15 thereof and make possible a more satisfactory bearing for the side cutters. At the same time, there has been made possible a more rugged support structure for the cross roller cutters. In addition, a structure has been disclosed in which 20 it is possible for the various cutter and bearing elements to be assembled and handled as a unit, after which they may be moved as a unit onto the bit head and secured thereto by suitable means such as welding or the like. A structure 25 has thus been illustrated which is capable of accomplishing all of the objects and advantages sought by this invention.

Having described my invention, I claim:

1. In a roller bit, a pair of side cutters adapted 30 to cut at the sides and bottom of a hole, a pair of cross-cutter bearing pins, each extending downwardly and inwardly toward the center of the bit, and being straight throughout its entire length, and cross roller cutters mounted on 35 said bearing pins, said cross roller cutters being of such extent as to traverse substantially the entire area of the bottom of a hole within the path of said side cutters.

2. In a roller bit, a pair of side cutters adapted 40 to cut at the sides and bottom of a hole and each having a relatively long inwardly extending bearing portion, a pair of cross roller cutters extending transversely of the bit, a pair of substantially straight shafts on which said roller cutters 45 are mounted, said shafts extending inwardly and downwardly with respect to the axis of rotation of said bit to clear said relatively long bearing portions, said pair of roller cutters being of such length as to alone traverse substantially the 50 entire area of the bottom of a hole within the path of said side cutters.

3. In a roller bit, a pair of side cutters adapted to cut at the sides and bottom of a hole and each having an anti-friction radial bearing adjacent 55 its outer end, a thrust bearing intermediate its ends, and a friction radial bearing adjacent its inner end, and a pair of cross roller cutters extending transversely of said bit and each having an axis extending inwardly and downwardly 60 with respect to the axis of rotation of said bit to clear said friction radial bearings.

4. In a roller bit, a pair of side cutters adapted to cut at the sides and bottom of a hole and each having a relatively long inwardly extending bearing portion and a pair of cross roller cutters extending transversely of said bit and each having an axis extending inwardly and downwardly with 65 respect to the axis of rotation of said bit to clear said relatively long bearing portions; and a bridge 70 member bridging the space between said side cutters and extending between said cross roller cutters to form a support for the inner ends of said cross roller cutters.

5. In a roller bit, a pair of side cutters adapted 75

to cut at the sides and bottom of a hole and each having an anti-friction radial bearing adjacent its outer end, a thrust bearing intermediate its ends, and a friction radial bearing adjacent its inner end, a pair of cross roller cutters extending transversely of said bit and each having an axis extending inwardly and downwardly with respect to the axis of rotation of said bit to clear said friction radial bearings, and a bridge 10 extending between the inner ends of said side cutters and between said cross roller cutters and forming a support for the inner ends of said cross roller cutters.

6. In a roller bit, a pair of side cutters adapted 15 to cut at the sides and bottom of a hole, and a pair of cross roller cutters extending transversely of said bit and each having an axis extending inwardly and downwardly with respect to the axis of rotation of said bit, cross cutter bearing pins 20 extending through said cross roller cutters, re-

spectively, and arms extending upwardly from the outer ends of said pins for supporting the same, said arms having their inner surfaces adjacent their lower ends extending upwardly and inwardly substantially at right angles to said cross cutter pins, whereby the cross section areas of said arms will increase upwardly. 5

7. In a cutter and bearing assembly for a roller bit, a bridge having downwardly and inwardly inclined spindles adjacent its opposite ends, side cutters rotatably mounted on said spindles, cross cutter pins extending upwardly and outwardly from the intermediate portions of said bridge, cross cutters rotatably mounted on said pins, and securing arms extending upwardly from the outer ends of said spindles and said cross cutter pins respectively for securing said assembly to a bit head 10 15
